UNITED STATES PATENT OFFICE.

HERBERT GEORGE UNDERWOOD, OF NEW YORK, N. Y., ASSIGNOR, BY DIRECT AND MESNE ASSIGNMENTS, TO THE INTERNATIONAL POWER VEHICLE COMPANY, OF WEST VIRGINIA.

SPEED-GOVERNOR FOR EXPLOSIVE-ENGINES.

SPECIFICATION forming part of Letters Patent No. 666,828, dated January 29, 1901.

Original application filed December 14, 1899, Serial No. 740,326. Divided and this application filed April 25, 1900. Serial No. 14,297. (No model.)

To all whom it may concern:

Be it known that I, HERBERT GEORGE UNDERWOOD, a citizen of the United States, residing in the borough of Manhattan, in the city, county, and State of New York, have invented certain new and useful Improvements in Speed Controllers and Governors for Explosive-Engines, of which the following is a specification.

10 My invention has for its object to provide means whereby the amount of a liquid hydrocarbon fed to an explosive-engine may be varied by an attendant for varying the speed of such engine and be automatically varied by 15 the engine for governing the speed thereof, so that the attendant may set the controlling apparatus for any speed within the limits of the engine and so that such speed when attained by the engine will be automatically 20 kept constant by the governor.

For the purpose of accomplishing the object above set forth my invention consists in the construction, arrangement, and combination of the several parts of which it is composed, as will be hereinafter more fully described and claimed.

Referring to the accompanying drawings, in which corresponding parts are designated by corresponding marks of reference, Figure 1 is a side elevation of an explosive-engine having my present invention applied thereto. Fig. 2 is a section on line Z Z of Fig. 4, showing the details of the eccentric-governor. Fig. 3 is a section taken on line Y Y of Figs. 2 and 4. Fig. 4 is a transverse section taken on line W W of Figs. 2 and 3.

While in the accompanying drawings I have shown my present invention as applied to an explosive-engine such as is described 40 in my other application for patent for improvements in explosive-engines, filed in the United States Patent Office on the 14th day of December, 1899, and serially numbered 740,326, of which application this present application is a division, it will be understood 45 that my present invention may be used with other forms of explosive-engines using liquid hydrocarbon as fuel.

The explosive-engine is provided with an

explosion-cylinder *a* and with a main shaft *c*, carrying one or more fly-wheels *b*. At a convenient point, as above the explosion-cylinder, is located a liquid-hydrocarbon reservoir *13*, connected, by means of a suitable pipe *12*, with an oil-pump *11*, which is in turn connected with the explosion-cylinder by a pipe *19*. A plunger *18* is provided for the pump, the plunger being actuated by a rod *21*, pivoted thereto and connected with a lever *22*, pivoted at *23* on the engine-frame. The lower end of the lever carries a roller tappet *24*, adapted to be actuated by a cam or eccentric *25*, revolving with the main crank-shaft *c* and carried on the hub *26* of the fly-wheel *b*. The eccentric consists of a circular hub *25^a*, having an elongated slot *25^b* therein, and a weighted tailpiece rigidly secured thereto in a line with the major axis of the slot. The hub *26* of the flywheel is contained within the slot *25^b*, and the tailpiece is provided with a guiding-tongue *28*, entering into a recess *29* in the rim of the fly-wheel and being pressed by a spring *30*, the tension of which may be adjusted by the screw *31*.

In the operation of the engine at the normal speed for which it may be adjusted the spring *30*, acting in opposition to the centrifugal force of the weight *27* of the eccentric due to the rotation thereof with the fly-wheel, holds the eccentric sidewise on the hub at a point intermediate of its movement as permitted by its slot *25^b*, thus giving the eccentric-hub eccentricity in respect to the fly-wheel hub and crank-shaft, whereby on each revolution of the crank-shaft the roller *24* on the lower end of the lever *22* will be forced rearwardly, actuating, through the lever *22* and rod *21*, the plunger *18* to make its driving stroke. The return stroke of the plunger is effected by a retractile spring *32* when permitted by the further rotation of the eccentric. Upon a decrease of speed of rotation of the fly-wheel due to any cause the centrifugal force of the weight upon the eccentric becomes reduced and is overcome to a corresponding extent by the force of the antagonistic spring *30*, so that the eccentric is shifted radially upon the fly-wheel and the eccentricity

of its hub increased to a corresponding extent, giving a longer stroke to the oil-pump plunger and increasing the amount of explosive material furnished to the explosive-engine. In a similar manner upon an increase in the speed of the engine the centrifugal force of the weight increases and overcomes the spring 30 to a sufficient extent to move the eccentric upon the fly-wheel in the opposite direction, thereby reducing the eccentricity and the length of stroke of the pump-plunger. As shown in Figs. 2 and 3, the hub of the fly-wheel has a collar 33 secured thereto concentric with the crank-shaft and upon which the roller 24 runs except when thrown by the eccentric. The parts are so proportionate that upon an excessive speed of the engine the eccentric will be shifted, as before described, to an extent sufficient to cause the eccentric-hub not to project at any point beyond the collar 33, whereby as the roller-tappet will then run upon the collar 33 no impulse will be imparted to the pump-plunger until the speed of the engine has been so far cut down as to again permit the eccentric-hub to project beyond the collar.

In Figs. 2, 3, and 4 I have shown the eccentric and weight connected therewith as mounted on the fly-wheel by means of pivoted links 34, and in this case the tongue 28 may be disconnected from the eccentric-tail, as it is not necessary that the weight should be guided thereby.

I thus provide governing means for automatically holding the speed of the engine constant for the speed at which it may be set by the attendant, and for the purpose of readily adjusting the engine for different speeds (which when attained will be held constant by the governor before described) I provide means whereby the amount of oil supplied to the engine may be varied at the will of the operator, thus permitting him to vary the speed of the engine, and for this purpose I form a slot 35 in the lever 22, connecting the rod 21 to the lever at the slot in the latter, and attach to the rod a link 36, having a threaded upper end, on which a nut 37, having a roughened edge, works, whereby as the nut is turned the point of attachment of the rod to the lever may be varied, being moved toward or from the roller 24 on the end of the lever, effecting a corresponding change in the throw of the pump-plunger and in the quantity of oil discharged thereby into the engine-cylinder. A spring 38 is arranged in proximity to the nut and is adapted to engage in the roughened edge thereof to hold it in the position in which it may be set.

Having thus described my invention, what I claim is—

1. In a governor for explosive-engines, the combination with a shaft driven by the engine, of a collar concentrically mounted upon the shaft, an eccentric rotating with and mounted to move radially in respect to the shaft under the influence of centrifugal force, a pump

for supplying a liquid hydrocarbon to the engine, and a tappet, actuating the pump and thrown by the eccentric, or resting upon the concentric-collar on the shaft, according to the radial position of the eccentric, substantially as described.

2. In a governor for explosive-engines, the combination with an eccentric, consisting of a slotted circular hub and a weighted tail-piece rigidly connected together, a shaft, driven by the engine, passing through the slot in the eccentric and rotating the eccentric, a collar mounted concentrically upon the shaft, a spring for normally holding the eccentric radially upon the shaft in opposition to the centrifugal force of the weighted tailpiece, a pump, supplying a hydrocarbon to the engine, and a tappet actuating the pump and thrown by the eccentric or resting upon the concentric collar on the shaft according to the radial position of the eccentric, substantially as described.

3. In a governor for explosive-engines, the combination with a shaft and wheel driven by the engine, of a weighted slotted eccentric, mounted upon the shaft, links, pivoted at their opposite ends to the wheel and eccentric and guiding the latter, the eccentric being otherwise independent of the wheel, a spring for normally holding the eccentric radially upon the shaft in opposition to centrifugal force, and a pump, supplying a liquid hydrocarbon to the engine, actuated by the rotation of the eccentric and according to the position thereof, substantially as described.

4. In a governor for explosive-engines, the combination with a shaft driven by the engine, of a wheel mounted thereon and having a projecting hub and annular flange, a collar mounted on the hub concentrically with the shaft, an eccentric consisting of a slotted circular hub and a weighted tailpiece rigidly connected together, the eccentric-hub being mounted upon the wheel-hub within the annular flange on the wheel, links, having their opposite ends pivoted to the wheel and to the eccentric to guide the latter, a spring-pressed pin mounted in the flange of the wheel and bearing upon the tailpiece to move the eccentric radially on the hub in opposition to the centrifugal force of the weighted tailpiece, a pump, supplying a hydrocarbon to the engine, and a tappet actuating the pump and thrown by the eccentric or resting upon the concentric collar on the shaft, according to the radial position of the eccentric, substantially as described.

5. In a speed varying and controlling device for an explosive-engine, the combination with a shaft driven by the engine, of a movable eccentric rotating with the shaft and the position of which in respect to the shaft varies with the speed of the engine, a pivoted slotted lever, a tappet upon the said lever thrown by the eccentric and according to the position thereof, a pump, supplying a liquid hydrocarbon to the engine, a pump-plunger, a rod

pivoted to the pump-plunger, and engaging the slot in the lever, a link, supporting the rod, and a nut upon the end of the link, whereby the point of attachment between rod and lever may be changed and the quantity of oil fed upon each stroke of the pump varied, substantially as described.

6. In a speed-controlling device for an explosive-engine, the combination with a pivoted slotted lever rocked by the movement of the engine, a pump-plunger, a rod pivoted to

the pump-plunger, and engaging the slot in the lever, a link supporting the rod, and a nut upon the end of the link, whereby the point of attachment between rod and lever may be changed and the quantity of oil fed upon each stroke of the pump varied, substantially as described.

HERBERT GEORGE UNDERWOOD.

In presence of—

GEO. W. MERCER,

SAMUEL G. FRANKLIN.
